SHELF FOR A ROOM DIVIDER OR SIMILAR ARTICLE

E. Burton Benjamin, Highland Park, Ill., assignor to Queen Manufacturing Co. Inc., Chicago, Ill., a corporation of Illinois

Filed Apr. 6, 1964, Ser. No. 79,345

Term of patent 14 years

(Cl. D33—3)

FIGURE 1 is a top plan view of my design for a shelf for a room divider or similar article;

FIGURE 2 is a side view of my design for a shelf for a room divider or similar article;

FIGURE 3 is an end view of my design for a shelf for a room divider or similar article;

FIGURE 4 is a bottom plan view of my design for a shelf for a room divider or similar article;

FIGURE 5 is a sectional view on an enlarged scale and taken along the line 5-5 of FIGURE 1; and

FIGURE 6 is a sectional view on an enlarged scale and taken along the line 6-6 of FIGURE 1.

I claim:

The ornamental design for a shelf for a room divider or similar article, as shown.
